UNITED STATES PATENT OFFICE.

EDWARD N. ANDERSON, OF CHICAGO, ILLINOIS.

CARD-CASE.

982,758.

Specification of Letters Patent. Patented Jan. 24, 1911.

Application filed March 30, 1910. Serial No. 552,454.

To all whom it may concern:

Be it known that I, EDWARD N. ANDERSON, a citizen of the United States, residing at Chicago, county of Cook, and State of Illinois, have invented certain new and useful Improvements in Card-Cases, of which the following is a specification.

My invention relates to improvements in card cases and more particularly to means for detachably securing a pack of cards to a member provided in the case, the object of the invention being to provide simple and effectual means of this character which shall be convenient in use.

15 A further object of my invention is to so attach the cards to the holding means therefor that they shall be protected against injury and soiling and more especially at the ends thereof.

20 Other objects will appear hereinafter.

With these objects in view my invention consists in the novel construction and arrangement of parts which will be herein-after fully described and more particularly 25 pointed out in the appended claims.

My invention will be more readily understood by reference to the accompanying drawing forming a part of this specification, and in which,

30 Figure 1 is a perspective view of a card case embodying my invention in its preferred form, Fig. 2 is a perspective view showing the case partly open to expose the card securing means therein, and Fig. 3 is 35 a perspective view showing a pack of cards and the means of holding the same in position.

Referring now to the drawing, 1 designates an ordinary card case having a pocket 40 2 therein for receiving a flap 3. The latter is tapering in form and is formed integral with the card backing member 4 on which the cards are arranged as shown in the several views. Cemented to the flap 3 is a fabric or textile member 5 which is co-extensive 45 with the width of the backing member 4. The member 5 is provided with a free portion to which the ends of the cards 6 are cemented, white rubber cement being the preferred cement used. After the cards are 50 arranged on the backing member 4 the ends thereof which are to be attached to the textile member 5 are treated with a suitable grease, white tallow being preferred. The 55 extent of the greased portion is included between the dotted lines 7, as indicated in Fig.

3. Cement is now applied to the inner surface of the free portion of the member 5 when said member is pressed securely against the ends of the cards. This causes 60 the portion of the ends of the cards which are outside of the dotted lines 7 to be firmly cemented to the member 5 while the greased portion will prevent the cement from adhering firmly to said ends. The process is 65 completed by applying a coat of cement to the exterior side of the member 5 which causes said member to be impregnated with cement.

It has been found that when cement is applied to either side of the member 5 the same is rendered flexible so that the cards may be moved slightly relative to each other without being easily detached from said member. Moreover, when each side of the 75 member 5 is treated with cement the upper edge thereof is prevented from fraying after a part of the cards have been removed. When a card is detached there is substantially no cement adhering to the end thereof 80 which was cemented to the member 5, all of the cement remaining on said member.

While I have shown what I deem to be the preferable form of my improved card case, I do not wish to be limited thereto as there might be various changes made in the details of construction and arrangement of parts described without departing from the spirit of my invention, and hence I desire to avail myself of such variations and modifications as fairly fall within the scope of the appended claims.

Having described my invention what I claim as new and desire to secure by Letters 95 Patent is:—

1. The combination with a pack of cards, of an end member cemented to the ends of said cards at their sides only, the central portions of said cards being free, substantially as described.

2. The combination with a pack of cards, of an end fabric member cemented to the ends of said cards at their sides only, the central portions of said cards being free, and said fabric member being also provided with cement on its back portion substantially as described.

3. The combination with a casing provided with a pocket, a card backing member having a flap inserted in said pocket, a textile member secured to said flap and having a free portion cemented to the ends of said

cards, there being white grease applied to the central portions of the ends of said cards where they are cemented to said textile member, and white rubber cement applied to each side of said free portion for impregnating the latter, substantially as described.

In testimony whereof I have signed my name to this specification in the presence of two subscribing witnesses.

EDWARD N. ANDERSON.
